UNITED STATES PATENT OFFICE.

JOHN WALDHEIM, OF ELIZABETH, NEW JERSEY, ASSIGNOR TO UNDERWOOD ELLIOTT FISHER COMPANY, OF NEW YORK, N. Y., A CORPORATION OF DELAWARE.

TYPEWRITING MACHINE.

Application filed September 4, 1923, Serial No. 660,724. Renewed October 24, 1924.

- This invention relates to continuous billing typewriting machines, in which a continuous web comprising plies of work-sheets, with successive forms printed thereon, may be fed with interleaved carbon-sheets around a cylindrical platen, and in which the carbon-sheets are shiftable at intervals from the typed forms to fresh untyped forms.
- More particularly, the invention relates to the improvements which may be used with machines disclosed in my co-pending applications, Serial No. 648,705, filed June 30, 1923 (now Patent No. 1,586,343, dated May 25, 1926), and Serial No. 659,273, filed 15 August 25, 1923 (now Patent No. 1,631,565, dated June 7, 1927), in which there is provided a pivoted carbon-carrier to which the ends of the carbon-sheets are attached, and which may be actuated to withdraw the carbon-sheets around the platen preparatory to shifting the carbon-sheets to a fresh set of forms. A relatively fixed table is also provided over which the web may be stretched to support the latter, when the carbon-carrier 20 is actuated; the platen in the type of machine disclosed in said applications remaining in its normal typing position during carbon-shifting operations.
- In my co-pending application 659,273, the table over which the web may be stretched preparatory to the carbon-shifting operation is curved, so that said web may extend tangentially from said table to the carbon-carrier, when the latter is in its operated position, and tangentially from said table to the platen, said table being fixed on a sub-carriage connected to the typewriter-carriage. When the carbon-carrier is returned to its normal position, a loop is produced to facilitate the line-spacing of said web around the platen, thus overcoming any possibility of slippage between the web and said platen during rapid line-spacing operations of said platen.
- A feature of the present invention is the provision of a pivoted table which is normally ineffective and hangs down behind the machine, and which may be raised to an effective position simultaneously with the carbon-carrier, when the latter is operated to withdraw the web around the platen to free the carbon-sheets therefrom preparatory to a carbon-shifting operation. With this arrangement the table is lowered during the return of the carbon-carrier, thus permitting the loop to be formed more readily in the web. With this arrangement the machine is also more compact when the parts are in their normal position.
- Another feature of the invention relates to means to lock the carbon-carrier and the swingable table in their operated positions to prevent accidental return thereof during a carbon-shifting operation.
- Other features and advantages will hereinafter appear.
- In the accompanying drawings, Figure 1 is a side elevation, partly in section, of an Underwood typewriting machine, showing the invention applied thereto, the parts being in their normal typing position.
- Figure 2 is a view similar to Figure 1, showing the carbon-carrier and the table operated to condition the web for a sheet-shifting operation.
- Figure 3 is a top plan view of the machine, the parts being in the position shown in Figure 1.
- Figure 4 is a fragmentary side sectional view, showing the table still in its raised position and the carbon-sheets held while the work-sheets are shifted relatively thereto and to a gage.
- Figure 5 is a diagrammatic side view, showing the carbon-carrier and the web-conditioning table returned to their normal positions, and the web fed with its leading edge to a second gage to bring the carbon-sheets to the printing point and the bottoms of the typed forms to a knife where they may be severed from the web.
- The invention is shown as applied to an Underwood standard typewriting machine, in which type-bars 10, when operated by keys, not shown, swing upwardly and rearwardly to print against the front of a cylindrical platen 11, mounted on a carriage 12 comprising end bars 13 connected to each other by a rear bar 14 and a front bar, not shown, said carriage being mounted for letter-feed movements on a rear rail 15 and a front rail, not shown, said rails being supported on the main frame 16 of the machine. The platen is secured to a shaft 17 journaled in end plates 18 of a platen-frame 20, said end plates being secured to each other by a bar 21 and a rear paper-table 22, over which a composite work-web 23 is led from the back of the machine to the rear and beneath

the platen where there are provided feed-rollers 24 and 25 to assist in feeding the work-web around the platen. The platen may be rotated by a finger-wheel 26 or line-space wheel 27, the latter being operable by suitable line-space mechanism, not shown. The platen-frame is supported on the carriage-frame for case-shifting movements in the usual way to present the platen to lower-case types 30 or upper-case types 31 on the type-bars. The feed-rollers may be released by mechanism operable by the regular feed-roller-release handle 28, so as to provide an unobstructed path around the platen when adjusting the work-web around the platen.

The web 23 may extend upwardly from any suitable source of supply over a guide-bar 32, supported on a carbon-carrier 34, the various plies 35, of which the web may be composed, extending between carbon-carrying bars 36, detachably mounted on stepped standards 37, secured to a cross-bar or plate 38 of the carbon-carrier. Carbon-sheets 40, the rear ends of which are connected to said bars 36, become interleaved between the web-plies or work-sheets 35, and extend from the carbon-carrier with said work-sheets, in the form of a loop 41, to a web-conditioning table 42, and then down over the rear paper-table 22 to the platen, as previously described. The carbon-carrier 34 and the web-conditioning table 42 normally occupy the positions indicated in Figure 1, but are pivotally supported at 43 and 44, respectively, on a sub-carriage 45, connected to travel with the typewriter-carriage 12, by brackets 46.

The sub-carriage comprises two downwardly-extending arms 47 to support a rock-shaft 48, to which two arms 50 of the carbon-carrier 34 are secured, and about the axis of which shaft the carbon-carrier may be swung, as hereinafter described. The sub-carriage comprises at its lower end a cross-bar 51 connecting the downwardly-extending arms 47, said cross-bar being provided with one or more rollers 52 to run on a rail 53, supported by suitable brackets 54, secured to the main frame 16 of the machine. Guards 55 are provided to prevent the sub-carriage from leaving the rail.

After a set of forms has been typed, it is necessary to shift the carbon-sheets from the typed set of forms to a fresh set of untyped forms before the typed set is severed. In order to shift the carbons, the web must be first so conditioned to facilitate such shifting. In order to do this, the web is withdrawn around the platen to free the carbon-sheets from said platen, as indicated in Figure 2. This may be done by drawing forwardly an operating handle 56, pivoted at 44, to pull upwardly on a link 57 to swing a bell-crank 58, pivoted on a stud or shouldered screw 60, secured to the left member

of the downwardly-extending arms 47 of the sub-carriage. Said bell-crank 58 is provided with a pin 61 extending into a slot 62 formed in forward extension 63 of one of the carbon-carrier arms 50, so that upon actuation of the bell-crank 58 the carbon-carrier is swung rearwardly and downwardly from the Figure 1 position to the Figure 2 position, thus retracting the carbon-sheets with the work-sheets about the platen. To assist in conditioning the web it is stretched over the web-conditioning table 42. Said table is actuated simultaneously with the operation of the carbon-carrier 34 and is raised to the position indicated in Figure 2. To this end the rock-shaft 48 is provided with an arm 64 connected with said table by means of a link 65 which is pushed upwardly during the actuation of the carbon-carrier to swing the table about its pivot 44, the table being brought to rest when the arm and link reach dead center (Figure 2).

The feed-rollers 24 and 25 may then be thrown on and the platen may be rotated to feed the work-sheets 35 and advance or shift them relatively to the carbon-sheets 40, the extent of shifting depending on the length of forms used and being determined by an indicator or gage 66 of a gage-element 67, adjustably secured by means of a thumbscrew 68 to a staff or gage-bar 70, carried by a cross-bar 71, secured to the end plates 18 of the platen-frame, the parts being thus brought to the position indicated in Figure 4. The carbon-carrier and the web-conditioning table are then restored to their normal positions indicated in Figure 5, thus producing the loop 41 in the web which rests on the table 42. The platen may then again be rotated to advance the work-sheets with the carbon-sheets, thus bringing the leading edges of the work-sheets to a second gage 72 of the gage-element. During this feeding of the work-sheets, the bottoms of the typed forms are brought to a knife 73, where they may be severed, and the carbon-sheets are brought to the printing point, so that the typing of the fresh set of forms may be proceeded with. The formation of the loop 41 produces slack in the web 23 to facilitate line-spacing of said web around the platen, thus eliminating the possibility of slippage between the web and the platen, which may otherwise result.

The web-conditioning table 42 comprises two end walls 74 to re-enforce it. It is pivotally supported at one end by a stub-shaft 75 (Figure 3), secured to a boss 76 on the right-hand wall 74, said stub-shaft bearing in an upturned ear 79 on one of the supporting brackets 46. The other end is supported by a shouldered screw 77 passing through a boss 78 on an ear 80 of the left-hand bracket 46, said screw being threaded into a boss 81 formed on the inside of the

left-hand wall 74 of the table 42. The screw 77 also forms a support for the operating handle 56.

The carbon-carrier is locked in its operated position to prevent accidental return thereof to hold the carbon-sheets during the sheet-shifting operation. This is done by arresting the bell-crank 58 in dead-center position (Figure 2), so that any force acting on the bell-crank from the carbon-carrier works directly against the pivot-screw 60 of the bell-crank. In a similar way, the table-lifting link 65, which is brought to a dead-center position, also locks the table in its actuated position to withstand downward pressure against said table, which is caused by the web. To limit the movement of the carbon-carrier in both directions, the pin 61 of the bell-crank 58 engages the end 20 of the slot 62 in the extension 63.

The web is held against sidewise movement by side guides 82 on the guide rod 32 and side guides 83 on the paper-table 22.

Variations may be resorted to within the scope of the invention, and portions of the improvements may be used without others.

Having thus described my invention, I claim:

1. In a continuous billing typewriting machine, the combination of a carriage, a platen on said carriage around which a continuous web comprising work-sheets with interleaved carbon-sheets may be fed, a carbon-carrier, a table, said carbon-carrier and said table being mounted independently of each other on said carriage, and a single finger-piece connected to said table and said carbon-carrier, and conditioned to simultaneously move the same upon their independent mountings.

2. In a continuous billing typewriting machine, the combination of a carriage, a platen on said carriage around which a continuous web comprising work-sheets with interleaved carbon-sheets may be fed, a carbon-carrier, a table, said carbon-carrier and said table being mounted independently of each other on said carriage, a single finger-piece to actuate said table and said carbon-carrier, said finger-piece mounted on said carriage, and linked connections between said finger-piece, said table and said carbon-carrier by which the two last-mentioned elements may be actuated simultaneously by said finger-piece.

3. In a continuous billing typewriting machine, the combination of a carriage, a platen on said carriage around which a continuous web comprising work-sheets with interleaved carbon-sheets may be fed, a sub-carriage connected to travel with said carriage, a carbon-carrier pivoted on said sub-carriage, a table pivoted on said sub-carriage, a handle to operate said carbon-carrier, and a permanently related interme-

diate connection between said carbon-carrier and said table to actuate the latter.

4. In a continuous billing typewriting machine, the combination of a carriage, a platen on said carriage around which a continuous web comprising work-sheet may be fed, a sub-carriage connected to travel with said carriage, a carbon-carrier pivoted on said sub-carriage, a table pivoted on said sub-carriage, a handle to operate said carbon-carrier, a rock-shaft to which the carbon-carrier is secured and which forms a fulcrum for said carbon-carrier, an arm on said rock-shaft, and a link connecting said arm with said table to cause said table to be actuated with said carbon-carrier.

5. In a continuous billing typewriting machine, the combination of a carriage, a platen on said carriage around which a continuous web comprising work-sheets with interleaved carbon-sheets may be fed, a pivoted carbon-carrier normally positioned near the platen, a pivoted curved table, said carbon-carrier and said table being arranged to travel with said carriage, means including a finger-piece to swing said carbon-carrier away from said platen to withdraw the web around said platen to free the carbon-sheets therefrom, and means connecting said carbon-carrier with said table to swing the latter to an ineffective position to support the web and assist in conditioning it for a work-sheet shifting operation.

6. In a continuous billing typewriting machine, the combination of a carriage, a platen on said carriage around which a continuous web comprising work-sheets with interleaved carbon-sheets may be fed, a sub-carriage, a carbon-carrier pivoted on said sub-carriage and normally positioned behind said platen, a normally-ineffective curved table pivoted on said sub-carriage, a finger-piece pivoted on said sub-carriage to swing said carbon-carrier rearwardly to withdraw the web around said platen to free the carbon-sheets from said platen, and a link connection between said carbon-carrier and said table to swing the latter upwardly to an effective position to support the web and assist in conditioning it for a work-sheet-shifting operation.

7. In a continuous billing typewriting machine, the combination of a carriage, a platen on said carriage around which a continuous web comprising work-sheets with interleaved carbon-sheets may be fed, a carbon-carrier, a table, said carbon-carrier and said table being mounted independently of each other on said carriage, a single finger-piece to actuate said table and said carbon-carrier, and means to lock said carbon-carrier and said table in their actuated positions.

8. In a continuous billing typewriting machine, the combination of a carriage, a platen on said carriage around which a continuous web comprising work-sheets with interleaved

carbon-sheets may be fed, an extension on said carriage, a carbon-carrier pivoted on said extension to withdraw the web about said platen to free the carbon-sheets from 5 said platen, a curved table pivoted on said extension over which while in its actuated position the web may be stretched to condition it for shifting the work-sheets relatively to the carbon-sheets, a finger-piece, 10 and means operable by said finger-piece to actuate said carbon-carrier and said table, said means being also effective to prevent the return movement of said carbon-carrier and hold said table in its operated position 15 during a work-sheet-shifting operation.

9. In a continuous billing typewriting machine, the combination of a carriage, a platen on said carriage around which a continuous web comprising work-sheets with interleaved 20 carbon-sheets may be fed, an extension on said carriage, a carbon-carrier pivoted on said extension to withdraw the web about said platen to free the carbon-sheets from said platen, a curved table pivoted on said 25 extension over which while in its actuated position the web may be stretched to condition it for shifting the work-sheets relatively to the carbon-sheets, a finger-piece, a link connection between said finger-piece and said 30 carbon-carrier, and a link connection between said carbon-carrier and said table, said connections being brought to dead center in their actuated positions to prevent return of said table and said carbon-carrier during a work- 35 sheet-shifting operation.

10. In a continuous billing typewriting machine, the combination of a carriage, a platen on said carriage around which a continuous web comprising work-sheets with interleaved carbon-sheets may be fed, means including a normally-ineffective curved table to condition the web for a work-sheet-shifting operation, an operating handle, and means comprising a toggle between said handle and said table, which may be straightened when the table is actuated, to lock the table in its operated position.

11. In a continuous billing typewriting machine, the combination of a carriage, a 50 platen on said carriage around which a continuous web comprising work-sheets with interleaved carbon-sheets may be fed, an extension on said carriage, a carbon-carrier pivoted on said extension to withdraw the web 55 about said platen to free the carbon-sheets from said platen, a curved table pivoted on said extension over which while in its actuated position the web may be stretched to condition it for shifting the work-sheets relatively to the carbon-sheets, a finger-piece, and means operable by said finger-piece to 60 actuate said carbon-carrier and said table.

12. In a continuous billing typewriting machine, the combination of a carriage, a 65 platen on said carriage around which a com-

posite web comprising continuous work-sheets with interleaved carbon-sheets may be fed, a carbon-carrier, a table, said carbon-carrier and said table being mounted independently of each other on said carriage, a connection between said table and said carbon-carrier so that one may be rendered effective while the other is being rendered effective to condition the web for a carbon-shifting operation, means to advance the work-sheets relatively to the carbon-sheets, and means to lock said carbon-carrier and said table during the carbon-shifting operation. 70 75

13. In a continuous billing typewriting machine, the combination of a carriage, a 80 revoluble platen on said carriage around which a composite web comprising plies of continuous work-sheets and interleaved carbon-sheets may be fed, an extension at the rear of said carriage, a carbon-carrier supported on said extension, a table pivotally mounted on said extension, and over which the web may be stretched, to condition it for a carbon-shifting operation, and a single finger-piece on said extension to operate said 85 table and said carbon-carrier to retract the composite web around the platen to free the carbon-sheets from said platen. 90

14. In a continuous billing typewriting machine, the combination of a carriage, a 95 revoluble platen on said carriage around which a composite web comprising plies of continuous work-sheets and interleaved carbon-sheets may be fed, a table connected to the rear of said carriage, said table normally 100 extending downwardly from said carriage and being swingable to a raised position, a carbon-carrier mounted on said carriage independently of said table, to be actuated over said table, while the latter is being 105 raised, to retract the composite web around the platen to free the carbon-sheets from said platen and condition said web for a carbon-shifting operation, a single finger-piece on said carriage to actuate said carbon-carrier, means to lock the carbon-carrier in its 110 operated position, and means to lock said table in its raised position. 115

15. In a continuous billing typewriting machine, the combination of a carriage, a 115 platen on said carriage around which a composite web comprising continuous work-sheets with interleaved carbon-sheets may be fed, a normally ineffective table, a finger-piece to actuate said table to condition the 120 web for a shifting operation between the carbon-sheets and the work-sheets, a bell-crank connected with said finger-piece, an arm connected with said table, and a pin-and-slot connection between said arm and 125 said bell-crank.

16. In a continuous billing typewriting machine, the combination of a carriage, a platen on said carriage around which a composite web comprising continuous work- 130

sheets with interleaved carbon-sheets may be fed, a normally ineffective table, a finger-piece to actuate said table to condition the web for a shifting operation between the 5 carbon-sheets and the work-sheets, a bell-crank connected with said finger-piece, an arm connected with said table, and a pin-and-slot connection between said arm and said bell-crank, said arm and said bell-crank 10 being so disposed when the table is in its operated position that the arm works against the dead center of the bell-crank by pressure exerted on said table.

17. In a continuous billing typewriting 15 machine, the combination of a carriage, a platen on said carriage around which a com-

posite web comprising continuous work-sheets with interleaved carbon-sheets may be fed, a normally ineffective table, a finger-piece to actuate said table to condition the 20 web for a shifting operation between the carbon-sheets and the work-sheets, a bell-crank connected with said finger-piece, a rock-shaft, an arm on said rock-shaft, said arm being connected with said table, said arm 25 having a slot therein, and a pin on said bell-crank to engage in said slot, said arm and said bell-crank being so disposed when the table is in its operated position that the arm works against the dead center of the bell- 30 crank by pressure against said table.

JOHN WALDHEIM.
